(57) **CLAIM**

The ornamental design for a raised bed garden panel, as shown and described.

DESCRIPTION

FIG. 1 is a front side profile view of the raised bed garden panel;

FIG. 2 is a back side profile view thereof;

FIG. 3 is a top view thereof;

FIG. 4 is a bottom view thereof;

FIG. 5 is an end view thereof;

FIG. 6 is a view thereof, showing the end opposite from that shown in FIG. 5;

FIG. 7 is a top axonometric view thereof; and,

FIG. 8 is a top axonometric environmental view thereof. The raised bed garden panel is shown with a symbolic break. Any portion of the panel between the break lines forms no part of the claimed design. The broken lines represent environment and form no part of the claimed design.
